UNITED STATES PATENT OFFICE.

ALFRED W. BEUTTELL, OF STREATHAM, LONDON, ENGLAND.

ILLUMINATING APPLIANCE.

1,174,470.

Specification of Letters Patent.

Patented Mar. 7, 1916.

Application filed December 21, 1912. Serial No. 737,956.

To all whom it may concern:

Be it known that I, ALFRED WILLIAM BEUTTELL, a subject of the King of Great Britain, residing at Streatham, London, 5 England, have invented certain new and useful Improvements Relating to Illuminating Appliances, of which the following is a specification.

The present invention relates to the construction of transparent screens made of glass for use in conjunction with reflectors such for example as those reflectors having a uniform concave cross-section throughout their length which are commonly used 10 in combination with linear or straight sources of light, for instance with double ended lamps of the straight filament type.

In the specification accompanying my pending application for Letters Patent, Serial No. 737,957, filed December 21st, 1912, 20 I have described an improved construction of reflectors, of the kind referred to, and according to which the reflecting surfaces are obliquely corrugated for the purpose of dispersing the striae or streaks of light which commonly occur in the light reflected from such reflectors when they are formed with smooth surfaces. According to the present invention instead of or in addition to using such 25 corrugated reflecting surface I employ in front of the reflector and light source a glass screen or plate or strip of glass or its equivalent having one surface provided with raised or depressed portions preferably in the form 30 of oblique corrugations. These raised and depressed portions or corrugations in the glass or screen may extend in the same direction as or in a different direction from the direction in which the corrugations on 35 the reflector extend, should the latter be corrugated and the corrugations on one side of the glass or screen may extend in the same direction as or in a different direction from the direction in which the corrugations 40 on the other side of the glass or screen extend should said screen be corrugated on both sides. The effect of such a glass screen is similar to that of the corrugated reflector 45 above referred to, with the difference however that the streaks of light emanating from the reflector are dispersed by the corrugated glass screen by refraction, the streaks or successive portions of them being displaced alternately in opposite directions. 50 By increasing or decreasing the depth of the corrugations I may obviously obtain any

desired degree of dispersion; the corrugations or wave-like formation being of any desired form or type and of any desired obliquity. The glass screen or strip, corrugated as aforesaid, may be either flat or curved in cross-section or any desired form other than flat. Also instead of or in addition to locating and using the corrugated glass screen in front of the reflector I may 60 form the reflector itself of such corrugated glass silvered or treated in any suitable manner on the back thereof to form a reflecting surface.

According to this last modification of the 70 present invention the refraction or dispersion referred to will take place at the corrugated surface thereof before the radiation from the light source reaches the reflector or reflecting surface instead of or in addition 75 to the refraction or dispersion taking place afterward.

Referring to the accompanying drawings Figure 1 is a plan view of a flat glass screen according to the present invention, corrugated in one direction only on its upper surface. The same figure will also serve to represent the appearance of a screen corrugated on both sides thereof in the same direction. If, however, one of these improved 80 screens be corrugated on opposite sides thereof in opposite directions, this Fig. 1 will also represent the direction of the corrugations of the opposite side thereof if the screen be turned over. Fig. 2 is an elevational sectional view of Fig. 1 on the line 2-2 where the screen is corrugated in one direction on one side only. Fig. 3 is a similar view where the corrugations are formed on both sides of the glass screen. Fig. 4 is 85 a sectional view of an illuminating device having a concentrating reflector and provided with a screen according to the present invention. Figs. 5 and 6 are sectional views of sheets of glass corrugated according to 90 the present invention and silvered or treated on the back thereof to form reflectors or reflecting surfaces. Fig. 7 is a sectional view of an example of an illuminating appliance provided with such a reflector according to the present invention. Fig. 8 is 95 a view of a lamp of the straight filament type.

Referring now to Fig. 4, the illuminating appliance consists of a reflector body B provided on the concave side thereof with a separate reflector or reflecting surface A

which for the sake of example, I have shown as a concentrating or intensifying reflector having a smooth surface or one liable to produce in practice accidental variations in the 5 illumination therefrom. Within the concavity of the reflector A is located a lamp or light source C, which is preferably an incandescent lamp of the straight filament type,—that is, a lamp which provides an extended 10 uni-directional source of light, and on the opposite side thereof the curved glass screen D shown for the sake of example corrugated on both sides thereof. Lamps of the straight filament type are shown in Fig. 15 8 and also in my Patent No. 1,107,650, granted August 18th, 1914. This lamp C is supported in position on the reflector body by any suitable holding means indicated as 20 C'. Obviously, however, screens according to the present invention may be of any other desired or suitable size or shape according to the particular appliance in conjunction with which they are used.

Referring now to Fig. 5 the glass sheet is 25 shown corrugated on one side only and on the opposite side is provided with a reflecting surface, shown by the thick line A.

Similarly in Fig. 6 the thick line A represents the reflecting surface provided on 30 one side of the glass sheet which in this figure, however, is shown corrugated on both sides thereof.

Referring now to Fig. 7 the reflector body B incloses the concentrating or intensifying 35 reflector E made according to the present invention and of a corrugated glass sheet corrugated on one side thereof in accordance with Fig. 5. The reflector E is provided with the reflecting surface A on that side of 40 the corrugated glass sheet farthest removed from the source of light C. The illuminating appliance shown in Fig. 7 is chosen only for the sake of example, it being understood that any desired form of illuminating 45 appliance may be made with reflectors according to the present invention. In this last modification as shown in Fig. 7 the radiation from the light source C falling upon the reflector E is refracted at the corrugated 50 surface of the reflector, is then reflected at the surface A and is again refracted in passing back through the said corrugated surface. Also any such illuminating appliances may be provided further 55 if desired with separate corrugated glass screens D as shown in Fig. 4.

From an inspection of the drawings it

will be apparent that each of the glass screens or other transparent light refracting member preferably extends longitudinally, 60 that it may be curved in cross-section throughout its length and that it is provided with raised or depressed or corrugated portions on one or both surfaces and that these last mentioned portions extend diagonally 65 to the longitudinal axis of the screen and also diagonally to the source of light which is preferably comprised of one or more incandescent filament sections.

The improvements herein set forth are 70 not limited to the precise construction and arrangement shown and described, as they may be embodied in various forms and modifications without departing from the spirit and scope of the invention. 75

What I claim is:

1. In an illuminating appliance of the class described the combination with an extended uni-directional source of light and a reflector concave in cross-section located 80 behind said source of light, of a plate of transparent material provided with corrugations obliquely disposed to the direction of the source of light for the purpose described of slightly blending by refraction the approximate rays from the source of light and the reflector while substantially maintaining the direction of the same. 85

2. The combination with an incandescent electric lamp of the straight filament type 90 and a holder therefor, of a member providing a reflecting surface behind the lamp, which reflecting surface is concave in cross-section, there being a transparent medium located in front of the reflecting surface and 95 in the path of the light rays, said transparent medium having surface corrugations that extend diagonally to the filament section or sections of said lamp.

3. An illuminating appliance of the class 100 described having a reflector concave in cross section, an incandescent electric lamp for producing a straight line source of light, means for supporting the electric lamp on the concave side of the reflector, and a transparent plate screen having parallel surface corrugations which are obliquely disposed to the source of light. 105

This specification signed and witnessed this 3rd day of December, A. D. 1912.

ALFRED W. BEUTTELL.

Signed in the presence of—

AUSTIN B. BOLEMAN,

EDWIN A. PACKARD.
